DOOR GRILLE

Laddie F. Hutar, Chicago, Ill.

Application November 8, 1954, Serial No. 33,002

Term of patent 14 years

(Cl. D54—2)

Fig. 1

To all whom it may concern:

Be it known that I, Laddie F. Hutar, have invented a new, original, and ornamental Design for Door Grille, of which the following is a specification, reference being had to the accompanying drawing, forming a part hereof.

Fig. 1 is a front elevational view of a door grille showing my new design; and

Fig. 2 is a side elevational view thereof.

The dominant features of my design are shown in solid lines.

I claim:

The ornamental design for a door grille, as shown and described.
